2 SHEETS—SHEET 2.

UNITED STATES PATENT OFFICE.

JOHN P. GARDNER, OF SOLDIERS HOME, CALIFORNIA.

RAIL FASTENER.

1,421,682.

Specification of Letters Patent. Patented July 4, 1922.

Application filed September 27, 1921. Serial No. 503,606.

To all whom it may concern:

Be it known that I, JOHN P. GARDNER, a citizen of the United States, residing at Soldiers Home, in the county of Los Angeles and State of California, have invented certain new and useful Improvements in a Rail Fastener; and I do hereby declare the following to be a full, clear, and exact description of the invention, such as will 10 enable others skilled in the art to which it appertains to make and use the same.

The object of the invention is to provide a simple railroad rail fastener for use in connection with ties of wood, concrete, metal 15 or any other preferred material, and more particularly to provide a fastener constructed on general principal of that disclosed in my former Patent No. 1311386, granted July 29, 1919, which contemplated 20 its use more especially in connection with a tie of the metallic I beam type; and with this object in view the invention consists in a construction, combination and relation of parts of which a preferred embodiment is 25 shown in the accompanying drawing, wherein:

Figure 1 is a plan view of rail fasteners constructed in accordance with the present invention applied in the operative position 30 to a tie and having rail portions engaged thereby.

Figure 2 is an elevation of the same shown on a plane taken transversely of the track rails.

Figure 3 is a detail sectional view on the plane indicated by the line 3—3 of Figure 1.

Figure 4 is a sectional view taken transversely through Figure 3 on the plane indicated by the line 4—4 of Figure 1.

Figure 5 is a detail view in perspective of the base plate of the fastener.

Figure 6 is a similar view of the bolt.

Figure 7 is a similar view of one of the clips forming the guides in which the bolts 45 are fitted, and

Figure 8 is a view similar to Figure 4 illustrating the application of the rail fastener to a metal tie of I-beam form in cross section.

The fastener, which is adapted to be supported by a tie 10 of any preferred construction and material, consists essentially of a base plate 11, preferably of steel and of about one-fourth of an inch in thickness to 55 afford the requisite strength and of substantially rectangular form adapted to cover

the upper surface of the tie to which it may be secured by means of bolts 12 or equivalent fastening means, together with guides carried by said base plate at opposite sides of the plane of the rail 13 for the reception of rail holding bolts 14 for engaging the rail foot or base 15.

The interval between the guides is preferably gaged to correspond with the width of the rail foot or base and each guide consists of complemental clips 15 having an attaching flange 16 and an upstanding flange 17, the attaching flange being adapted for attachment to the base plate by means of rivets 18. The upstanding flanges of complemental clips are arranged in substantial parallelism, perpendicular to the plane of the base plate and are spaced apart to suit the width of the bolt 14 which is to be received therebetween, said bolt being beveled and under cut at its inner end as shown at 18' to form an inclined face to bear upon the upper surface of the rail foot or base and through the engagement therewith to prevent creeping of the rails. At the outer end of the face 18 the bolt is provided with an abrupt shoulder 19 to bear against the edge of the rail foot or base to prevent spreading of the rails.

The upper edges of the upright walls or flanges of the clips are at their outer end portions turned laterally inward to form guide lips 20 to overhang the bolt and prevent upward displacement thereof as they are moved to place in engagement with the rail foot or base, and said walls or upright flanges of the clips at their inner end portions are extended upward to form ears 21 in which are provided openings 22, registering transversely of the guides for the reception of a key 23, preferably of the split type, the upper surface of the bolt having a transverse groove or seat 24 for registration with said openings 22 and hence engagement by the key.

A cushioning pad 25 of fibre or similar material may be arranged on the upper surface of the base plate between the guides to form a yielding seat for the rail.

From the above description it will be obvious that the rail fastener may be constructed independently of the tie and rail and attached to the tie which may be of any suitable material, in the most convenient manner to suit the material of the tie, and that the employment of the guides on the

base plate do not serve to weaken the same by reason of the fact that they are formed of clips which are attached to the plate and hence serve rather as reinforcing elements therefor and as abutments to hold the cushioning pad in proper position.

Having thus described the invention, what I claim is:—

1. A rail fastener for attachment to a rail tie, the same consisting of a base plate provided at opposite sides of and perpendicular to the rail seat with guides which are thus disposed perpendicular to a rail arranged on said seat, bolts slidingly fitted in said guides and provided at their inner ends with means for engaging the rail foot or base, and means for locking said bolts in rail engaging position, said guides consisting of complementary clips having base flanges riveted to the base plate and upstanding parallel flanges arranged in spaced relation.

2. A rail fastener for attachment to a rail tie, the same consisting of a base plate provided at opposite sides of and perpendicular to the rail seat with guides which are thus disposed perpendicular to a rail arranged on said seat, bolts slidingly fitted in said guides and provided at their inner ends with means for engaging the rail foot or

base, and means for locking said bolts in rail engaging position, said guides consisting of complementary clips having base flanges riveted to the base plate and upstanding parallel flanges arranged in spaced relation with their upper edges inturned to overhang the bolt arranged therein.

3. A rail fastener for attachment to a rail tie, the same consisting of a base plate provided at opposite sides of and perpendicular to the rail seat with guides which are thus disposed perpendicular to a rail arranged on said seat, bolts slidingly fitted in said guides and provided at their inner ends with means for engaging the rail foot or base, and means for locking said bolts in rail engaging position, the walls of the guides being extended to form ears having transversely registering openings, and said fastening device consisting of a cross pin engaging said openings, the bolts having a transverse seat for the reception of said pin.

In testimony whereof I affix my signature in presence of two witnesses.

JOHN P. GARDNER.

Witnesses:

HERMAN HOUSEN,
SAMUEL SELFRIDGE.
